UNITED STATES PATENT OFFICE.

JOSEPH WATSON, OF PETALUMA, CALIFORNIA.

FUMIGATOR.

SPECIFICATION forming part of Letters Patent No. 352,282, dated November 9, 1886.

Application filed March 23, 1886. Serial No. 196,262. (No model.)

To all whom it may concern:

Be it known that I, JOSEPH WATSON, a citizen of the United States, residing at Petaluma, in the county of Sonoma and State of California, have invented a new and useful Improvement in Smoking Apparatus, of which the following is a specification, reference being had to the accompanying drawings.

My invention relates to an improvement in 10 smoking apparatus for exterminating ground-squirrels, gophers, and other burrowing noxious animals; and it consists in the peculiar construction and combination of devices that will be more fully set forth hereinafter, and 15 particularly pointed out in the claims.

In the drawings, Figure 1 is a side elevation of my invention. Fig. 2 is a vertical sectional view of the same. Fig. 3 is a similar view taken on a plane at right angles to Fig. 2.

20 A represents the fire-chamber, which is preferably cylindrical in shape, and the lower portion of which forms the frustum of a cone, as at B, and the said fire-chamber has an inner wall, C, and an outer wall, E, a space or chamber being thus left between the walls surrounding the fire-chamber. Openings F are made 25 in the inner wall, near the upper edge thereof, which communicate with the interior of the fire-chamber, and on the lower end of the said inner wall is secured a cap, G, which forms 30 the bottom of the fire-chamber.

H represents a conical spout, which is secured on the lower edge of the outer wall of the fire-chamber, the space between the inner 35 and outer walls of the fire-chamber communicating with the upper end of the said spout.

I represents a short horizontal tube, which is open at both ends, and passes through the walls of the fire-chamber near the bottom thereof, and the said tube is provided at its outer 40 end with the removable cap or plug I'.

K represents a tube, which is secured on the inner side of the fire-chamber, and extends vertically therein, the said tube being 45 open at its upper and lower ends.

To the upper end of the fire-chamber is hinged a cover, L, which is provided with a hook or catch, L', for securing it to the fire-chamber when closed thereon, and through 50 the said cover passes a vertical pipe, M, the

lower end of which communicates with the upper end of the pipe K when the cover is closed.

On the upper end of the pipe M is located a double-ended bellows, N, which is provided 55 with two valves, O, but one of which is shown, which admit air into opposite ends of the bellows alternately, and the bellows are also provided with openings P, which communicate with the upper end of the pipe M. The 60 fire-chamber is provided with suitable handles, R, by means of which it may be readily carried about.

The operation of my invention is as follows: 65 A fire is kindled in the fire-chamber and supplied with any suitable fuel which will create a dense smoke, and sulphur or any other poisonous compounds or chemical will be added thereto, if desired. The discharge end of the spout H is then inserted in the hole in the 70 ground made by the squirrel or other animal to be exterminated and the bellows are operated, which causes strong currents of air to pass down through the pipes M and K into the fire-chamber and create active combustion 75 therein and force the smoke therefrom through the openings in its inner wall into the annular space or chamber, and from thence down through the spout into the hole in the ground. Continued operation of the bellows causes the 80 smoke and fumes to permeate every portion of the underground passage or burrow and kill the animals therein.

The function of the tube I and the cap I' is 85 to permit the fire to be lighted without having to raise the cover of the fire-chamber.

By employing a compound or double-ended bellows a constant draft of air is caused to pass through the apparatus and to force out dense volumes of smoke and fumes therefrom. 90

Having thus described my invention, I claim—

1. The combination of the fire-chamber A, having the openings F near its upper end, the outer casing, E, surrounding the fire-chamber, 95 and thereby forming the chamber C, the spout H, secured to the lower end of the casing E, the tube I, passing from the fire-chamber out through the outer casing and having the cap or plug, and the pipe K, for conducting a 100

blast of air to the bottom of the fire-chamber, for the purpose set forth, substantially as described.

2. In a smoking apparatus, the combination of an outer shell, a fire-chamber having a closed bottom and inclosed within the outer shell and out of contact therewith to form an intermediate space or chamber, the openings F, formed in the fire-chamber near its upper end and communicating with the chamber of the fire-box and the intermediate space, a spout attached to the lower end of the outer shell beneath the fire-chamber and having an open contracted discharge end to conduct the smoke, &c., from the intermediate space or chamber into the hole or burrow, and a bellows on the upper end of the fire-chamber, substantially as described, for the purpose set forth.

3. In a smoking apparatus, the combina-

tion of an outer tapering shell, a fire-chamber 20 having a closed lower end and the openings F in its upper end, and arranged within and out of contact with the outer shell to form an intermediate space or chamber, a conical discharge-spout connected to the lower end of 25 the outer shell and arranged beneath the fire-chamber, a bellows supported on the top of the fire-chamber, and a vertical pipe, K, communicating with the bellows and terminating above the bottom of the fire-chamber, substantially as described, for the purpose set forth. 30

In testimony that I claim the foregoing as my own I have hereto affixed my signature in presence of two witnesses.

JOSEPH WATSON.
